UNITED STATES PATENT OFFICE.

LEON VAN DYCK, OF BRUSSELS, BELGIUM, ASSIGNOR TO THE COMPAGNIE CONTINENTALE D'INCANDESCENCE ET DE CHAUFFAGE, (SYSTEMES FRANK & POITRIMOL,) OF SAME PLACE.

APPARATUS FOR SUPPLYING COMBUSTIBLE LIQUID UNDER PRESSURE TO BURNERS.

SPECIFICATION forming part of Letters Patent No. 683,819, dated October 1, 1901.

Application filed December 24, 1897. Serial No. 663,353. (No model.)

To all whom it may concern:

Be it known that I, LEON VAN DYCK, a subject of the King of Belgium, residing at Brussels, Belgium, have invented certain new and useful Improvements in Apparatus for Supplying Combustible Liquid Under Pressure to the Burners of Lamps or Heating Apparatus, (for which I have obtained patents in Belgium, No. 129,671, dated July 24, 1897, and No. 130,567, dated September 8, 1897, and in Great Britain, No. 27,233, dated November 20, 1897,) of which the following is a specification, reference being had to the accompanying drawing.

This invention relates to lamps; and it includes certain peculiar features hereinafter described and claimed.

The drawing shows the improved lamp in vertical central sectional elevation.

The arrangement shown is particularly applicable to all kinds of suspension lights or lamps, such as lyre-shaped lamps, also to street-lamps and generally to every description of illuminating apparatus of that class.

By describing merely as an example a "lyre-shaped" arrangement such as is frequently used in apartments fitted with apparatus in accordance with this invention a sufficiently clear idea of the principle embodied in the device will be given.

Referring to the drawing, *a* designates the liquid-fuel reservoir, and *b* the screw-plug employed to close the filling-orifice of the same, the joint being made perfectly air-tight.

c is the supply-tube, through which the liquid fuel is forced to the burner, which is of the "gasifying" type and which may be of any suitable construction.

h is an upper air-tight secondary reservoir to which the liquid fuel poured into the primary reservoir *a* may rise under adequate pressure through the pipe *g*.

f is a pipe bent toward the dome of the primary reservoir *a* and forming an extension of one arm of a lyre, which leads to a close air-tight chamber *l*, the other arm of the lyre being formed by the pipe *g*. The lower end of the pipe *f* is above the lower ends of the pipes *d* and *e*.

m is a pointed screw-tap, by operating which the pipe *f* and chamber *l* may be connected with or disconnected from the atmosphere. The chamber *l* is air-tight and may contain either air only or, preferably, air and minute particles of charcoal, which when used serve to increase the effective capacity of the space in which they are placed, for it is well known that charcoal absorbs seven or eight times its volume of atmospheric air, which it liberates again, however, in proportion as its temperature rises and reabsorbs once more as it cools down. The employment of charcoal thus renders the apparatus highly serviceable by enabling the chamber *l* to be of a convenient dimension while being sufficiently powerful in its action.

The operation of the device is extremely simple. During the initial heating of the burner by means of alcohol or any other means after the plug or tap *m* has first been turned off the air in the charcoal is liberated and expands under the influence of the heat radiating from the lamp-chimney. It exerts a rapidly-increasing pressure upon the fluid in the primary reservoir *a*, which accordingly rises both through the tube *c* into the burner *d* and if the pressure be excessive also through the tube *c* into the secondary reservoir *h*. By the time the fluid reaches the burner it becomes converted into vapor, (or gas,) ignites, and from that moment assumes the task of continuing to heat or maintaining the temperature of the chamber *l*. Presently there is restored, as it were, an equilibrium of temperatures as regards the said chamber—viz., between the heat gained by it and the heat it loses by radiation. At this juncture the liquid fuel ceases to ascend to the secondary reservoir *h*, and the apparatus continues to work under the constant pressure supplied by the column raised as long as there is any liquid left in said secondary reservoir. If the flame has to be extinguished before all this liquid has been consumed, it is only necessary to operate the pointed screw-tap *m*. The air will then escape through the narrow orifice *o*, the liquid contained in the reservoir *h* will redescend into the reservoir *a*, the flame will go out, the

chamber *l* will cool down, the charcoal will reabsorb air through the orifice *o*, which has remained open, and eventually the apparatus is ready to be kindled anew.

5 Having described the invention, what I claim is—

1. In a lamp for burning liquid fuel, the combination of a primary liquid-fuel reservoir, a burner located over the reservoir having a pipe entering said reservoir, an airtight chamber over the burner, a pipe connecting the liquid-fuel reservoir with said chamber a secondary reservoir located above said first-mentioned reservoir and also above said chamber, and a pipe connected with the secondary reservoir and leading into the primary reservoir and the lower end of the same being below the lower end of the second-mentioned pipe.
- 15 2. In a lamp for burning liquid fuel the combination of a primary liquid-fuel reser-

voir, a secondary reservoir located above the other one, a pipe connected with the secondary reservoir and leading into the primary reservoir, a burner having a depending pipe 25 leading into the primary reservoir and the lower end of the same being below the lower end of the first-mentioned pipe, a pipe projecting into the primary reservoir and extending upward therefrom and having an air-30 orifice, a plug for controlling said orifice, and a chamber communicating with said last-mentioned pipe, and located in vertical line with and above the burner and between said burner and secondary reservoir. 35

In testimony whereof I have hereunto set my hand this 14th day of December, 1897.

LEON VAN DYCK.
